UNITED STATES PATENT OFFICE,

JAMES B. REPLOGLE, OF CHICAGO, ILLINOIS, ASSIGNOR TO JOSEPH SALTZMAN, OF CHICAGO, ILLINOIS.

CLOTHES-PRESSING MACHINE.

No. 882,841.

Specification of Letters Patent. Patented March 24, 1908.

Application filed April 2, 1906. Serial No. 309,312.

To all whom it may concern:

Be it known that I, JAMES B. REPLOGLE, a citizen of the United States, residing at Chicago, in the county of Cook and State of Illinois, have invented certain new and useful Improvements in Clothes-Pressing Machines, of which the following is a specification.

My invention relates to improvements in clothes pressing machines, and more particularly to foot power toggle lever presses, of the type illustrated in my prior application, Serial Number 286,552 filed Nov. 9, 1905.

One of the salient objects of my invention is to provide a power system for toggle lever presses whereby the labor of the operator is minimized, the pressure efficiency of the machine increased, and the pressure application rendered steadier or more even.

A further object of my invention is to provide means for maintaining the pressure between the working surfaces of the press notwithstanding inequalities in the working surfaces or in the character of the material acted upon.

Another and further object of my invention is to provide an improved heating system for the buck or stationary press member, and in addition thereto to provide an efficient, economical and compact heat generator for direct association with the buck, as a component part of the machine.

Yet another object of my invention is to provide improved means for securing proper alinement and lateral adjustment of movable elements of the power system, to insure the most efficient working of the machine and take up lateral lost motion of the beam.

Other and further objects of my invention will best become apparent to those skilled in the art from the following description, taken in conjunction with the accompanying drawings, wherein:

Figure 1 is a side elevation of a machine embodying my invention. Fig. 2 is a horizontal central section of my improved press buck; Fig. 3 is a vertical elevation with parts in section of the heating system of my machine complete; Fig. 4 is a sectional detail of a yielding, or spring, toggle-link, and Fig. 5 is a sectional detail of a side motion adjustment for the beam guiding link. Figs. 6 and 7 are details of the heating drum.

Throughout the drawings like numerals of reference refer always to like parts.

In the drawings 10 indicates in general the

frame of my machine, of any usual or desired construction and configuration, embodying the usual bed plate or table 11, and suitable bearings for the parts hereafter described.

The press buck, to be hereafter more fully described, is supported above the bed 11 and associated therewith is the usual press iron 12, preferably heated in any desired manner, and supported as usual upon an arm 13

comprising telescoping sections, the outer section whereof is pivotally secured in the usual manner, to the vertical movable beam 14 of the power system. To the bottom of the movable beam is pivotally connected as

at 14' the treadle lever 15, having an upwardly extending arm, or lever, 16, constituting one of the members of the toggle construction, said arm 16 being connected through a toggle link to be hereafter more fully

described, with an arm 17, pivoted as at 18 in a suitable bearing in the frame and adjustable to vary the position of its outer extremity through the agency of the screw 19 bearing upon a suitable rigid part of the frame.

A movable beam 14 is positioned and guided in its motion relative to the frame, by parallel links 20—20 of equal effective length, each pivoted at its opposite extremity to the beam 14 and the frame 10 respectively.

One or more suitable springs 21, are interposed between the lever 15 and a suitable part of the frame, to exert a constant tension upon the lever 15, tending to elevate the entire movable system, to raise the press iron 12

out of contact with the buck. This general association of parts is described in my prior application and forms no part of my present invention save in its association with the

features hereinafter described.

In general it will be understood that when power is applied, as through the medium of the operator's foot, to the forward extremity of the treadle lever 15, the entire movable

system is forced downward against the tension of spring, or springs, 21, through the action of the toggle lever, which finds fixed bearing on arm 17, so that the press iron 12 is brought toward the underlying buck. It

will be apparent that the pressure applied by the press iron upon the buck will be dependent upon the power exerted to depress the treadle lever 15 after the coacting press

parts are brought into engagement, and that this pressure will, therefore, be dependent somewhat upon the strength and skill in the applicatio.

of the power of the operator.

To increase the effectiveness of the machine and equalize its action, and to reduce the work of the operator necessitated in the use of the machine, I provide means whereby power expended by the operator in the movement of the parts of the pressure system through the initial portion of their range of travel is conserved and automatically applied to the pressure system to increase the effective pressure at the termination of the movement of the moving system. To this end I provide a fly wheel 22, supported in suitable bearings upon the frame 10, and provide on the shaft 22' of said fly wheel, gear teeth constituting a gear 23, and I arrange in mesh with said gear 23 a rack rod 24, at its lower end pivotally connected as at 25 to the lever 15. A roller 26 is provided upon the frame for maintaining the rack rod 24 in its operative association with the gear 23. It will now be apparent that when the lever 15 is depressed the fly wheel 22 is set in rotation, and that when the lever 15 comes to rest, with the press iron in contact with and exerting a pressure upon the buck, the momentum of the fly wheel is translated into power applied to the lever 15, to effect the application of a high degree of pressure between said press iron and buck. As during the initial movement of the lever system, the operator has to overcome only the inertia of the parts and the tension of the spring 21, it will be apparent that he can readily set the fly wheel in rotation at relatively high velocity, the surplus power applied by the user being conserved and subsequently applied at the time when the greatest power is needed to supply the necessary pressure between the press iron and buck, and thereby obviate the necessity of an extra effort upon the part of the user at the termination of movement of the treadle lever, to effect the application of the requisite pressure. Furthermore, when the treadle lever 15 is released to permit the restoration of the parts to normal position by the action of spring 21, the fly wheel 22 acts as a governor to prevent unduly rapid restoration. The toggle link connecting the toggle lever 16 with the bearing lever 17, and generally indicated by the numeral 28, also forms a feature of my invention. Said link is formed of two members, normally held in extended relation by a strong spring and compressible to a limited degree against the tension of said spring. As best shown in Fig. 4, the link 28 is formed of two telescoping members 28' and 28'', the outer member 28'' whereof is recessed as at 29 to receive the member 28' and to receive also the strong coiled spring 30. A pin 31 secured in the member 28'' takes through a slot 32 in the member 28' and limits the relative movement of the telescoping members.

It will be apparent that with the ordinary

toggle construction the pressure exerted by the press iron upon the buck varies according to the angular relation of the toggle members, and that very slight inequalities in the surfaces of the buck and press-iron will result in undue variations in the pressure exerted upon the goods therebetween. My spring link 28 compensates for this deficiency. It will be apparent that when the lever 15 is depressed and the press iron brought down upon the buck with high degree of pressure the spring 30 will be compressed somewhat, so that if there occur inequalities in the surfaces between the buck and iron the spring 30 expands and, automatically lengthening the upper toggle member, presses the beam 14 downward and the press iron 12 into proper pressure contact with the material upon the buck. The spring link, therefore, is advantageous irrespective of the inertia device, or fly-wheel structure, hereinbefore described, but it is particularly advantageous in combination with such structure, as the spring 30 affords a means for taking up to some degree the strain upon the moving parts caused by the application of power stored in the fly wheel to the lever system when the press iron is brought to rest, and tends to prevent stripping of the teeth of the gear and rack rod.

For initially securing perfect alinement of the pivoted bearings of links 20-20, and taking up such lost motion of the beam 14 as may develop from use and wear, and for the purpose of laterally adjusting the beam structure with reference to the frame structure, I provide at each end of each of the links the adjustment construction illustrated in Fig. 5.

Specifically, in Fig. 5, 20 indicates the link provided with a bearing aperture 33 intersected by a recess 34 extending inward from the exterior of the link. The bearing 35 is provided upon the frame member 10, and is preferably of a depth not greater than the distance from the inner side of the link to the recess 34. In the recess 34 is provided a nut 36 having good lateral bearing upon the walls of the recess 34, and through which takes the cap screw 37, upon the stem whereof is provided the lock nut 38. Now it will be apparent that the cap screw 37, abutting against the bearing stud 35 may be adjusted axially to move the link 20 laterally outward upon its bearing stud 35 or permit its inward movement so that perfect lateral alinement may be secured between the bearings at the opposite ends of the link. Also if wear loosens the fit between apertures 33 of the links and bearing projections 35, so that side play of the beam 14 is permitted, such looseness may be taken up by adjustment of the cap screws 37 to throw the one end of each link inward and its other end outward so that the apertures 33 bind sufficiently on their

bearings to prevent the side play. Further said cap screws may be adjusted to laterally adjust the beam structure bodily with reference to the frame structure.

5 In my present machine, I provide a constantly heated buck by constructing a metal buck to admit of the circulation of the heated fluid therethrough, and I provide in association with the buck a novel and convenient 10 form of heat generator and fluid supply means, for supplying said heating fluid thereto.

Referring specifically to the drawings, 40 indicates in general the buck, supported upon the 15 suitable pedestal 41, supported upon the bed 11 of the machine, and conveniently secured to said pedestal by straps 42, and associated tension screws. The buck may be of any convenient shape, preferably thin in a vertical 20 direction, and is of hollow construction to provide for the passage of heated fluid therethrough, the passage afforded being preferably tortuous, and herein illustrated as comprising an intake leg 43 and an outlet leg 44 separated by a baffle plate 45, but communicating with each other at one end. Posts 46 are provided connecting the top and bottom plates of the buck to give the requisite vertical strength thereto without interference 25 with the circulation of the fluid.

30 47 indicates the inlet to the passage 43, and 48 the outlet from passage 44.

A heated fluid, such as hot water, may be supplied to the buck from any convenient 35 source, but I preferably provide as a component part of my machine a heat generator and hot water supply means, as best shown in Figs. 1 and 3. Referring particularly to 40 said figures, 50 indicates in general the generator comprising a cylindrical casing 51, divided by a partition 52 into an upper hot water chamber, or reservoir, 53, and the lower heating chamber 54. 55 indicates the burner base of the machine, to which is secured 45 a suitable gas burner 56, or other heat generator, the heat whereof passes through the chamber 54 and out through a suitable escape outlet 56'. A heating drum 57 having relatively large heating surface, is disposed 50 in the chamber 54, one end of said drum being connected with the reservoir 53, and the opposite lower end of the drum being connected 55 by a suitable pipe 58 with an outlet 48 of the buck. The water receptacle 53 is provided with an outlet 59 which communicates with the inlet 47 of the buck. 60 indicates a heavy removable cap or cover for the water receptacle 53, which acts as a safety valve to prevent undue accumulation of steam pressure 60 in the hot water system and permits the ready filling of the water receptacle.

It will be obvious that when the heater is 65 in operation the water circulation will be through the drum 57 to the receptacle 53, thence through the registering apertures 59

and 47 into the inlet leg of the passage through the buck, out through the outlet leg and the pipe 58 back to the bottom of the drum 57. Manifestly by regulation of the heat of the burner, the hot water system may 70 be used to impart any desired degree of heat to the buck lower than the boiling point of water, or the fluid contained therein.

While I have herein described in some detail a specific embodiment of my invention, 75 including a description of a definite type of machine as illustrative of a practical embodiment thereof, I do not desire to be understood as limiting my invention to the particular machine, or specific constructions herein 80 shown and described, as it will be apparent that numerous changes and modifications might be made in the construction without departure from the spirit and scope of my invention.

Having thus described my invention, what I claim and desire to secure by Letters Patent, of the United States, is:

1. In a press of the character described, coacting press members, one of which is movable, a lever system for moving said press member comprising a power initiating member arranged for limited oscillating movement, and means for applying to said lever system, at the termination of its movement, 95 power expended in the initial stages of movement of said lever system.

2. In a press, coacting press members, one 100 whereof is movable toward and from the other, a lever system for moving said movable member, comprising a manually operable power initiating lever and a fly wheel associated with said lever system, arranged to be set in movement by the initial movement of said lever system, and to apply power 105 to the lever system tending to create a pressure between the press members at the termination of the movement of said lever system.

3. In a toggle press, the combination with 110 the coacting press members, of a toggle lever system for moving one of said press members relative to the other, a fly wheel, a gear associated for rotation with said fly wheel, and a rachet meshing with said gear, connected with a member of the lever system.

4. In a toggle press, the combination with 115 the press member, of the vertical beam and a beam-moving toggle construction, one member of said toggle comprising interfitting parts, a spring for maintaining said members in relatively extended position, and means for limiting the relative movement of said parts in both directions, whereby said link is made yielding in the direction of its length.

5. In a toggle press, in combination, press 120 members, one of which is movable toward and from the other, a lever system comprising a manually operable power-initiating lever for moving said movable member, a fly wheel operatively connected with a member 130

of said lever system to be set in rotation during the initial portion of the movement of said lever system, and to translate its momentum into power applied to said lever system at the termination of its movement, and connections between said lever members to which the power of the fly wheel is applied and the movable press member including a yielding element.

10 6. in a machine of the character described, the combination with the coacting press members, of the movable beam 14, a frame, links connecting the movable beam with the frame, an adjustable bearing arm 17, the 15 spring-link 28 pivoted at one end to said arm, a toggle arm 16 pivoted to the opposite end of the spring link, and a lever 15.

7. In a press of the character described, coacting press members, a lever system for 20 moving one of said press members including an upright beam; a frame; a link connection between said beam and the frame, having a

bearing for pivotal movement on one of said parts; a nut seated in said link, and a cap screw taking through said nut and abutting 25 against the link-bearing whereby the said end of the link may be adjusted laterally on its bearing.

8. In a machine of the character described, the combination with the coacting press 30 members of a movable beam, a frame, links connecting the movable beam with the frame, a bearing arm pivoted to the frame, an adjustable stop for positioning the bearing arm with respect to the frame, toggle arms connecting the said bearing arm and the movable beam, and means for operating the toggle.

In testimony whereof I hereunto set my hand in the presence of two witnesses.

JAMES B. REPLOGLE.

In the presence of—

FORÉE BAIN,
MARY F. ALLEN.
